ELECTRIC DISCHARGE DEVICE

Otto Baier and Annemarie Katsch, Berlin, Germany, assignors to C. Lorenz Aktiengesellschaft, Berlin-Tempelhof, Lorenzweg, Germany, a company

Application May 13, 1938, Serial No. 207,754
In Germany May 15, 1937

4 Claims. (Cl. 250—27.5)

The present invention relates to electric discharge devices and more particularly to such devices adapted for generation of very high frequency oscillations.

5 As well known, the mechanical stability of electric discharge devices may be improved by making them entirely or partially of a ceramic material. Electron discharge tubes of this type are preferably employed for the generation of 10 very high frequency oscillations at which the inductance value of the leading-in conductors is of great importance and where normal sockets cannot be employed.

15 The present invention deals with such discharge tubes which essentially consist of a ceramic material and in which the leading-in conductors are formed as a bail and rigidly attached to the base portion of the discharge vessel at two points. The advantage obtained on account of the structure 20 of the electron discharge tube according to the invention is that this tube may be directly attached to a supporting means and that the lengths of the leading-in conductors to the various electrodes of the tube present minimum lengths.

25 The possibility for a displacement of the leading-in conductors which may occur when these leads are fixed only at one point is substantially avoided on account of the bail-shaped leading-in conductors and the method of fixing these leading-in conductors at two points.

30 The invention will be more readily understood from the following description taken in conjunction with the accompanying drawing, in which:

Fig. 1 is a cross sectional view through one embodiment according to the invention; Fig. 2 is a bottom view of the arrangement shown in Fig. 1; while Fig. 3 illustrates a modification over the arrangement shown in Fig. 1.

35 In the figures, 1 represents a cylinder of ceramic material carrying at its upper end a cover 2 of glass which is elongated in the shape of a pipe to which the vacuum pump is connected and which is sealed after an evacuation has been effected. The remote end of the cylinder 1 is 40 covered by a base portion 3. Two circular rows of holes 4 are arranged in the base portion 3 and extending throughout the entire thickness thereof. These holes are adapted to receive the bail-shaped leading-in conductors 5 which after having been brought into position are sealed to the 45 base portion at two points 6 so that lateral bending of these leads after the tube has been finished is not possible. Moreover, the tube may be directly placed in a fitting.

50 Fig. 3 illustrates a modification over the ar-

5 arrangement shown in Fig. 1. The difference between these two designs is that the leading-in conductors 5 are fixed in holes at the outer edge which merely project into the base portion 3.

The manufacturing of the tubes as above described is effected in such manner that the leading-in conductors are at first sealed to the base portion by the agency of a material having a high melting point such as hard glass or metal whereupon the various electrodes are attached to their 10 appertaining leading-in conductors. Finally, a material having a lower melting point is employed for the seal 8 between the cylindrical member 1 and the base portion 3.

15 It is also within the scope of the invention to apply the above described shape of the leading-in conductors to tubes of other types. The essential feature is that the leading-in conductors present the shape of a bail and are attached to the base portion of the tube at two points. 20

What is claimed is:

1. An electric discharge device comprising a discharge vessel composed of different portions, a plurality of electrodes arranged in said vessel, and leading-in conductors to the various electrodes, each of said leading-in conductors being 25 bail-shaped and sealed to said vessel at two points.

2. An electric discharge device comprising an envelope, a base portion of ceramic material, a plurality of electrodes arranged in said envelope, and bail-shaped leading-in conductors to said electrodes, said base portion having two circular rows of holes adapted to receive said leading-in conductors in radial relation to each other. 30

3. An electric discharge device comprising a discharge vessel having one cylindrical main portion, a glass cover sealed to one end and a ceramic base portion sealed to the opposite end thereof, a plurality of electrodes arranged in said envelope, and bail-shaped leading-in conductors 35 to said electrodes, said base portion having two circular rows of holes adapted to receive said leading-in conductors in radial relation to each other. 40

4. An electric discharge device according to 45 claim 1 and in which the different portions of which the discharge vessel is composed are held together by means of a seal and the leading-in conductors are sealed directly to the wall of the discharge vessel by means of a material having 50 a higher melting point than the seal holding together the different portions of the vessel.

OTTO BAIER,
ANNEMARIE KATSCH.
